UNITED STATES PATENT OFFICE.

STEPHEN EVANS ALLEY, OF GLASGOW, SCOTLAND.

GAS-COMPRESSOR.

SPECIFICATION forming part of Letters Patent No. 720,872, dated February 17, 1903.

Application filed November 18, 1902. Serial No. 181,872. (No model.)

To all whom it may concern:

Be it known that I, STEPHEN EVANS ALLEY, a subject of the King of Great Britain, residing at Glasgow, Scotland, have invented certain new and useful Improvements in or Relating to Gas-Compressors, of which the following is a specification.

This invention relates to air or other gas compressors of the type in which a differential piston reciprocates within a cylinder and forms therewith two or more compression-chambers, the gas being successively compressed in these chambers.

According to this invention a plurality of inlet and outlet valves is provided on the cylinder, an inlet-conduit is led from a source of air or other gas supply to one inlet-valve and thence to one of the compression-chambers, an outlet-conduit extends from that chamber

to an outlet-valve and thence to an inlet-conduit leading to another inlet-valve and thence to another of the compression-chambers, and another outlet-conduit is led from that other chamber to another outlet-valve. The moving part of each valve is operatively connected with that of the other similarly - acting valve, and means are provided for opening and closing the valves in proper sequence for predetermined periods. Preferably a plurality of valve-chests is provided on the cylinder for the inlet and outlet valves. In this case an inlet-conduit is led from the source of air or other gas supply to one inlet-valve chest and thence to one of the compression-chambers, an outlet-conduit extends from that chamber to an outlet-valve chest and thence leads to an inlet-conduit, to the aforementioned inlet-valve chest, and thence to another of the compression-chambers, and another outlet-conduit is led from that other chamber to the aforementioned outlet-valve chest. A plurality of sliding valves is disposed in the chests, one in the inlet-valve chest and in the inlet-conduits of that chest and constituting a partition between said inlet-conduits and another in the outlet-valve chest in the outlet-conduits of that chest and constituting a partition between said outlet-conduits.

In the preferred form of the gas-compressor according to this invention the gas which is successively compressed in the compression-

chambers of the cylinder is passed from one chamber through an intercooler and thence to another of the chambers. In this case the 55 outlet-conduit from the first compression-chamber passes to the intercooler, and an inlet-conduit connects the intercooler with the inlet-valve chest and thence passes to the other compression-chamber.

In the accompanying drawings, illustrating a preferred form of gas-compressor according to this invention, Figure 1 is a side elevation of the compressor, partly in section, on the line 1 1 of Figs. 2 and 3. Fig. 2 is a front 65 elevation of the compressor, half in section, on the line 2 2 of Figs. 1 and 3. Fig. 3 is a plan of the compressor, showing the positions of the valve-chests.

Like letters indicate like parts throughout 70 the drawings.

Referring to the drawings, a frame A supports a cylinder B, having a water-jacket A'. A differential trunk-piston is disposed in the cylinder and has a trunk C and two operating- 75 faces C' and C'', one of these, C', having a greater effective area than the other, C''. A crank-shaft D, mounted in bearings D' in the frame A, is operatively connected with the trunk C by a connecting-rod D''. A cylinder-cover B', together with the greater face of the piston C' and the cylinder, form the first compression-chamber b', and a projecting portion B'' on the cylinder, constituting the trunk-guide, forms with the lesser face C'' of the piston and the cylinder a second compression-chamber b''. An intercooler comprising a series of connected gas-tight pipes E is arranged under the frame A of the compressor. The casing E' of the intercooler serves as the base 90 of the frame A and contains cooling-water which encircles and cools the pipes E. Two valve-chests F F' are attached along one side of the cylinder, one of these, F, for an inlet-valve, and the other, F', for an outlet-valve. 95 An inlet - conduit G is provided from the source of air or gas supply to the inlet-valve chest F and thence to the first compression-chamber b'. An outlet-conduit G' extends from the first compression-chamber b' to the 100 outlet-valve chest F' and thence to the intercooler E. Another inlet-conduit H connects the intercooler E with the inlet-valve chest F and thence passes to the second compression-

chamber b^2 . Another outlet-conduit H' is led from the second compression-chamber b^2 to the outlet-valve chest F' , from which the compressed air or gas is discharged. Two piston sliding valves J J' are disposed in the valve-chests, one, J , in the inlet-valve chest F and arranged to control the two inlet-conduits G and H in that chest, the former by its upper end j^0 , which travels to and fro across it, and 10 the latter by its lower end j^{00} , which operates in like manner in relation thereto, and the other, J' , in the outlet-valve chest F' and arranged to control the two outlet-conduits G' and H' in the chest by its upper and lower 15 ends j' and j'' , respectively, which travel, like the ends of the inlet-valve, to and fro across them. Each piston sliding valve is provided with a gas-tight diaphragm J^2 , which enables the valve to serve also as a partition to separate 20 the two conduits of its chest. Two eccentricities K and K' are mounted on the crank-shaft, one, K , connected by an eccentric-rod L , cross-head M^2 , and valve-spindle M to the diaphragm J^2 of the inlet piston sliding valve 25 J , and the other eccentric, K' , connected by an eccentric-rod L' , cross-head M^3 , and valve-spindle M' to the diaphragm J^2 of the outlet piston sliding valve J' . Guides N for the cross-heads M^2 M^3 are provided on the 30 frame A .

The operation of the compressor is as follows: As the piston moves downward the upper end j^0 of the inlet piston-valve J opens the inlet-conduit G to the first compression-chamber b' , and gas enters that chamber during the downstroke of the piston. The upper end j^0 of the inlet valve-piston J then closes the inlet-conduit G , and the piston rises and compresses the gas up to a certain point when 35 the piston-face C' is approaching the cylinder-cover B' , when the upper end j' of the outlet piston-valve J' opens the outlet-conduit G' . The compressed gas then passes through the conduit G' to the intercooler E . At the same 40 time as compression takes place in the first compression-chamber b' the under face of the piston C^2 recedes from the projection B^2 . The lower end j^{00} of the inlet piston-valve J opens the inlet-conduit H , and gas passes from 45 the intercooler E through the conduit H into the second compression-chamber b^2 . When the piston is lowered, the lower end j^{00} of the inlet piston-valve J closes the inlet-conduit H , and the gas is compressed in the compression-chamber b^2 up to a certain point when 50 the lower piston-face C^2 is approaching the projection B^2 , when the lower end j'' of the outlet piston-valve J' opens the outlet-conduit H' and allows the compressed gas to be 55 discharged from the second compression-chamber b^2 through the outlet-conduit H' to a receiver or the like.

What I claim as my invention, and desire to secure by Letters Patent, is—

60 1. In a "stage" gas-compressor the combination of a differential trunk reciprocating piston, a cylinder containing it and divided

by the piston into two compression-chambers, a crank-shaft operatively connected with that piston, an inlet-valve chest, an outlet-valve chest, both chests extending along one side of the cylinder, an intercooler comprising a series of connected gas-tight pipes, an inlet-conduit from a source of gas-supply to the inlet-valve chest and thence to one of the two said compression-chambers, an outlet-conduit from that chamber to the outlet-valve chest and thence to the intercooler, an inlet-conduit from the intercooler to the inlet-valve chest and thence to the other of said compression-chambers, an outlet-conduit from that other chamber to the outlet-valve chest, two piston sliding valves one in the inlet-valve chest and in the inlet-conduits of that chest and constituting a gas-tight partition between them and the other in the outlet-valve chest and in the outlet-conduits of that chest and constituting a gas-tight partition between them, and two eccentricities on the crank-shaft one operatively connected to the inlet-valve 90 and the other to the outlet-valve.

2. In a "stage" gas-compressor the combination of a differential trunk reciprocating piston, a cylinder containing it and divided by the piston into two compression-chambers, a crank-shaft operatively connected with that piston, an inlet-valve chest, an outlet-valve chest, an intercooler comprising a series of connected gas-tight pipes, an inlet-conduit from a source of gas-supply to the inlet-valve 95 chest and thence to one of the two said compression-chambers, an outlet-conduit from that chamber to the outlet-valve chest and thence to the intercooler, an inlet-conduit from the intercooler to the inlet-valve chest and thence to the other of said compression-chambers, an outlet-conduit from that other chamber to the outlet-valve chest, two piston sliding valves one in the inlet-valve chest and in the inlet-conduits of that chest and constituting a gas-tight partition between them, and the other in the outlet-valve chest and in the outlet-conduits of that chest and constituting a gas-tight partition between them, and two eccentricities on the crank-shaft 100 one operatively connected to the inlet-valve and the other to the outlet-valve.

3. In a "stage" gas-compressor the combination of a differential trunk reciprocating piston, a cylinder containing it and divided by the piston into two compression-chambers, a crank-shaft operatively connected with that piston, an inlet-valve chest, an outlet-valve chest, an intercooler, an inlet-conduit from a source of gas-supply to the inlet-valve chest 105 and thence to one of the two said compression-chambers, an outlet-conduit from that chamber to the outlet-valve chest and thence to the intercooler, an inlet-conduit from the intercooler to the inlet-valve chest and thence to the other of said compression-chambers, an outlet-conduit from that other chamber to the outlet-valve chest, two piston sliding valves, one in the inlet-valve chest and in the inlet-conduits 110

of that chest and constituting a gas-tight partition between them, and the other in the outlet-valve chest and in the outlet-conduits of that chest and constituting a gas-tight partition between them, and two eccentrics on the crank-shaft one operatively connected to the inlet-valve and the other to the outlet-valve.

4. In a "stage" gas-compressor the combination of a differential trunk reciprocating piston, a cylinder containing it and divided by the piston into two compression-chambers, a crank-shaft operatively connected with that piston, an inlet-valve chest, an outlet-valve chest, an inlet-conduit from a source of gas-supply to the inlet-valve chest and thence to one of the two said compression-chambers, an outlet-conduit from that chamber to the outlet-valve chest and thence to an inlet-conduit to the inlet-valve chest and thence to the other of said compression-chambers, an outlet-conduit from that other chamber to the outlet-valve chest, two piston sliding valves one in the inlet-valve chest and in the inlet-conduits of that chest and constituting a gas-tight partition between them, and the other in the outlet-valve chest and in the outlet-conduits of that chest and constituting a gas-tight partition between them, and two eccentrics on the crank-shaft one operatively connected to the inlet-valve and the other to the outlet-valve.

5. In a "stage" gas-compressor the combination with a cylinder, a differential piston therein whereby said cylinder is divided into a plurality of compression-chambers, and with means for reciprocating the piston, of a plurality of valve-chests for inlet and outlet valves, an intercooler, an inlet-conduit from a source of gas-supply to an inlet-valve chest and thence to one of the said compression-chambers, an outlet-conduit from that chamber to an outlet-valve chest and thence to the intercooler, an inlet-conduit from the intercooler to the aforementioned inlet-valve chest and thence to another of said compression-chambers, an outlet-conduit from that other chamber to the aforementioned outlet-valve chest, a plurality of sliding valves one in the inlet-valve chest in the inlet-conduits of that

chest, and another in the outlet-valve chest in the outlet-conduits of that chest, and means for operating those sliding valves.

6. In a "stage" gas-compressor the combination with a cylinder, a differential piston 55 therein whereby said cylinder is divided into a plurality of compression-chambers, and with means for reciprocating the piston, of a plurality of valve-chests for inlet and outlet valves, an inlet-conduit from a source of gas-supply to an inlet-valve chest and thence to one of the said compression-chambers, an outlet-conduit from that chamber to an outlet-valve chest and thence to an inlet-conduit to the aforementioned inlet-valve chest and 60 thence to another of said compression-chambers, an outlet-conduit from that other chamber to the aforementioned outlet-valve chest a plurality of sliding valves one in the inlet-valve chest in the inlet-conduits of that chest, 65 and another in the outlet-valve chest in the outlet-conduits of that chest, and means for operating those sliding valves.

7. In a "stage" gas-compressor the combination with a cylinder, a differential piston 75 therein, whereby said cylinder is divided into a plurality of compression-chambers, and with means for reciprocating the piston, of a plurality of inlet and outlet valves, an inlet-conduit from a source of gas-supply to one inlet-valve and thence to one of the said compression-chambers, an outlet-conduit from that chamber to an outlet-valve and thence to an inlet-conduit to another inlet-valve and thence to another of said compression-chambers, an outlet-conduit from that other chamber to another outlet-valve, an operative connection between the moving part of each valve and that of the other similarly-acting valve, and means for opening and closing the 80 valves in proper sequence for predetermined periods.

In testimony whereof I have signed my name to this specification in the presence of two subscribing witnesses.

STEPHEN EVANS ALLEY.
